UNITED STATES PATENT OFFICE.

FRANK F. SIMPSON, OF THE UNITED STATES ARMY.

FOLDING BED.

1,311,719.

Specification of Letters Patent. Patented July 29, 1919.

Application filed December 9, 1918. Serial No. 265,921.

To all whom it may concern:

Be it known that I, FRANK F. SIMPSON, Lieut. Colonel, U. S. Army, a citizen of the United States, residing at city of Washington, in the District of Columbia, have invented certain new and useful Improvements in Folding Beds, of which the following is a description, reference being had to the accompanying drawing and to the figures of reference marked thereon.

My invention relates to new and useful improvements in folding beds.

An object of the invention is to provide a folding bed in which the usual link connection between the spring frame and head and foot may be tightly clamped and drawn upwardly to prevent any movement of the links, especially the objectionable rocking movement, so as to form a very rigid bed and at the same time provide means whereby the bed may be readily folded.

Another object of the invention is to provide a simple, cheap and effective locking means of this character which may be readily applied to the ordinary bed now in use and having certain details of structure and operation hereinafter more fully described.

In the accompanying drawings:

Figure 1 is a perspective view of the ordinary army bed now in use, showing my improved link locking means applied thereto;

Fig. 2 is an enlarged vertical sectional view showing the locking means in dotted lines in its released position;

Fig. 3 is a longitudinal sectional view taken at right angles to Fig. 2, and showing the locking means in its locked position;

Fig. 4 is an enlarged perspective view of the locking means detached from the spring frame and showing the cam detached from the hook;

Fig. 5 is a perspective view of a slightly modified form of locking hook;

Fig. 6 is a vertical longitudinal sectional view showing my invention applied to a bed in which a high foot and head is provided causing the use of a longer link to fold the head and foot under the spring frame;

Fig. 7 is an end view partly in section looking in a direction at right angles to Fig. 6;

Fig. 8 is an end view partly in section, similar to Fig. 7, showing a modified form of locking link and cam.

Referring now to the drawings, 1 repre-

sents the spring frame of an ordinary army cot or bed which is connected to the head 2 and foot 3 by means of the links 4 and 5. As shown, these links are arranged on each side of the spring frame and one is a long link and the other a short one, so that the head and foot may fold rearwardly and forwardly, respectively, under the spring frame. This structure of folding cot or bed is well known, but in such a structure, while the cot is firmly held in its set up position, the spring frame is not rigidly supported and has an objectionable movement due to the loose pivotal connections thereof. This movement or wabbling of the spring frame is objectionable, and, by attaching my improved hook and cam lock, it has been found that a very rigid cot or bed is produced, and which I will now describe.

The links 4 and 5 have their upper ends pivotally connected at 6 and 7 to the inner face of the vertical leg 8 of the angle iron 9, forming the side rail of the spring frame, and their lower ends pivotally connected at 10 and 11 to the outer face of the corner posts 12 of the foot and head of the bed. Pivotally connected to the end rails 13 of the spring frame, at 14, is a hook 15 adapted to have its hooked end 16 passed under the lower edge 17 of the upper link 4. The lower end of the hook has pivoted thereto, by the pivot 18, the cam member 19. The said cam member has a cam face 20 and an upwardly extending lug 21 at one side of the pivot 18, as clearly shown in the drawings. The cam or eccentric pivoted on the hook forces the links upwardly, clamping them tightly against the end of the frame, holding the springs in close contact with the links at the head or foot of the bed, and tightens the links on their pivots, while the hook, which forms a tight connection between the link and end rail, absolutely prevents any movement of the links, and, therefore, prevents any movement of the spring frame. The lug 21, carried by the cam, prevents the cam from being swung over too far, and also prevents the link from jumping off of the hook.

In the modification shown in Figs. 6 and 7 of the drawings and showing my invention as applied to a bed having a high foot and head, it is necessary to have a longer link in order that the foot and head may fold all the way under the spring frame. In such a bed the link 22 is pivotally connected

to the head or foot and the spring frame in the same manner as described in respect to the cot. The lower link 23 is pivoted at 24 to the head of the bed and its outer end is 5 provided with a lug 25 extending at an angle thereto and extending into a notch 26 in the lower edge of the link 22 and prevents the inward movement of the lower end of the head.

10 The vertical leg of the end rail of the spring frame has pivoted at 27 the downwardly extending hook 28, which has a notch 28' adapted to receive and hook over the lower edge of the link 23. Carried by 15 the pivot 27 is a cam 29 which has a cam face 30, so arranged that when the lower end thereof is swung downwardly, it engages the upper edge of the upper link 22, and by the hook engaging the lower edge 20 of the lower link, the two links are tightly drawn together, so that there can not possibly be any movement of the links. This locking of the links against movement locks the spring frame against the same movements and a very rigid bed is formed and 25 one which may be readily folded in the same manner as the cot.

In the modified form of locking means shown in Fig. 8, the cam lever 32 is pivoted at 33, so that the cam face will engage the upper edge of the link 22 the same as shown in Fig. 7, but, instead of having the hook 34 mounted on the pivot 33, it is mounted upon the pivot 35, carried by the 35 cam lever. By this arrangement, it will be seen that when the cam lever is swung downwardly, the cam face engages the upper edge of the link 22 and the hook draws up on the link 23 and firmly locks them together.

40 It will be understood that instead of arranging the links and clamps so that the latter clamp the links against the end of the frame, the links and clamps may be so arranged that the clamping action will take place against the sides of the frame.

Having thus described my invention, what I claim as new and desire to secure by Letters Patent, is:

50 1. A folding bed including a bed spring frame, head and foot sections, links for swingingly connecting said sections respectively to the bed spring frame and limiting the movement of said sections when in normal position for supporting the frame, hooks carried by the bed spring frame, and cams co-operating with the hooks and adapted to cause an upward pressure of the links,

whereby said sections are rigidly connected to said frame when in supporting position. 60

2. A folding bed including a bed spring frame, head and foot sections, links for swingingly connecting said sections respectively to the bed spring frame and limiting the movement of said sections when in normal position for supporting the frame, hooks carried by the bed spring frame and extending under the links, and cams carried by the lower end of the hooks and adapted to engage the lower edges of the links and cause 70 an upward pressure on the links, whereby said sections are rigidly connected to said frame when in supporting position.

3. The combination with a bed spring frame, head and foot, of a link pivotally connecting the frame to the head, a second link pivoted to the head and having its free end entering into positive engagement with the lower edge of the first mentioned link, a hook pivoted to the end of the spring 80 frame at right angles to the link and engaging the lower edge of the lower link, and a cam carried by the spring frame and engaging the upper edge of the upper link and clamping the two links in the hook. 85

4. The combination with a bed spring frame, head and foot, of a link pivotally connecting the frame to the head, a second link pivoted to the head and having its free end entering a notch in the lower edge of 90 the first mentioned link, a hook pivoted to the end of the spring frame at right angles to the link and engaging the lower edge of the lower link, and a cam carried by the spring frame and engaging the upper edge 95 of the upper link and clamping the two links in the hook.

5. The combination with a bed spring frame, head and foot, of a link pivotally connecting the frame to the head, a second 100 link pivoted to the head and having its free end entering a notch in the lower edge of the first mentioned link, a cam carried by the spring frame and adapted to engage the upper edge of the upper link, and a hook 105 pivoted to the cam and engaging the lower edge of the lower link when the cam is swung downwardly and drawing the two links together.

In testimony whereof, I affix my signature 110 in the presence of two witnesses.

FRANK F. SIMPSON.
